E. J. KNAPP,
SANCTUARY LAMP.
APPLICATION FILED APR. 28, 1919.

1,336,635.

Patented Apr. 13, 1920.

UNITED STATES PATENT OFFICE.

EDWARD J. KNAPP, OF SYRACUSE, NEW YORK, ASSIGNOR TO E. J. KNAPP CANDLE AND WAX CO., INC., OF SYRACUSE, NEW YORK, A CORPORATION OF NEW YORK.

SANCTUARY-LAMP.

1,336,635.

Specification of Letters Patent. Patented Apr. 13, 1920.

Application filed April 28, 1919. Serial No. 293,147.

To all whom it may concern:

Be it known that I, EDWARD J. KNAPP, a citizen of the United States, and a resident of Syracuse, in the county of Onondaga and State of New York, have invented 5 a certain new and useful Sanctuary-Lamp, of which the following is a specification.

This invention relates to candle lamps and has for its object certain improvements 10 in candle or sanctuary lamps of the type described in my Patent No. 1,255,614, Feb. 5, 1918, by which the candle and melted grease in the cupped base is caused to be almost entirely consumed and by which outlets and a receptacle is provided to receive 15 any grease running over the cupped base or down the candle which would otherwise obstruct the seating of the cap of the candle on the base and prevent proper 20 burning of the candle.

The invention consists in the novel features and in the combinations and constructions hereinafter set forth and claimed.

In describing this invention, reference is 25 had to the accompanying drawings in which like characters designate corresponding parts in all the views.

Figure 1 is a vertical sectional view of 30 this lamp, the candle being shown in elevation.

Figs. 2 and 3 are, respectively, a plan and inverted plan of the cupped base.

Fig. 4 is a vertical sectional view through 35 the cap and base, showing the cap seated on the base after the candle is nearly consumed.

1 designates the main frame or holder 40 of the lamp which is here shown as a tubular glass shell open at its top and having a depending bottom 2 which contracts inwardly and downwardly and terminates in an ornamental piece as a ball 3. The bottom confines a cavity for the receptacle to be hereinafter described.

45 The frame or holder is here shown as adapted for a hanging lamp and is provided with suitable means as chains 4 by means of which it may be carried or suspended.

50 The frame or holder may be of any other suitable form, size and construction.

5 is the cupped base in which the candle 6 is mounted and 7 is a receptacle in which the base 5 is seated, said receptacle includ- 55 ing an annular side wall and an inwardly

and downwardly extending bottom 8 extending into the cavity of the bottom 2 of the frame or holder 1.

The bottom of the receptacle adjoining the annular wall is annular and flat and 60 forms a seat or ledge 9 for the base 2. Said base is provided with a ring 10 which encircles the body of said base, and this ring is provided with an outwardly extending base flange 11 formed with corrugations 12 which are here shown as circular. The ring also has an upright conical peripheral surface 13 above the flange 11 with which the inner face of the cap engages. The ring 10 is preferably formed 70 of hard rubber while the cap 15 is formed of glass.

The annular wall of the receptacle 7 is spaced apart from the base 5 and the base is provided with spacing lugs 14 on its 75 lower side which rest on the ledge 9 and provide passages from the upper part of the receptacle 7 into the bottom 8 thereof for any melted wax or grease that may overflow the base 5 and otherwise accumulate 80 on the flange 11 or ring 10 or in the upper part of the receptacle, and prevent the cap 15 from seating on the ring 10. This cap 15 is substantially the same as in 85 my patent referred to.

In the lamp of my patent, the melted wax or grease sometimes overflowed the cupped base and accumulated on the ring so that the cap could not seat substantially evenly but by this construction and by the corrugations 90 11, most of the wax runs off and any remaining on the ring accumulates in the corrugation or is flattened in the corrugations as the cap seats.

In order that the butt of the candle or the 95 melted wax or grease may be almost entirely consumed the wick 16 of the candle is increased in thickness at 17 at its lower end so as to provide enough wick to draw the melted grease or wax as 18 in the cupped 100 base in sufficient quantity to feed the flame, or fast enough to prevent the flame from being smothered in the melted grease or wax.

As here shown the wick is held in the prongs 19 of a disk 20 at the lower end of the candle as in my patent referred to, and the wick is doubled back to increase the size of the wick in the butt of the candle. The bottom of the holder is also provided with suitable air holes 21.

This candle lamp construction is particularly advantageous in that any overflow from the candle is carried away or placed where it cannot materially affect the seating 5 of the cap and hence prevent the burning of the candle.

What I claim is:

1. In a candle lamp; a cup shaped base and a candle having its lower end in said base, the candle having the lower portion of its wick of greater thickness than the remainder of the wick which thickened portion of the wick is located in that part of the candle at the bottom of the cup shaped base, substantially as and for the purpose described.
2. A candle lamp including a cupped base having an outwardly extending annular flange formed with corrugated upper faces, a candle mounted in the base, and a cap on the candle having its lower end face movable into position to rest on said corrugated face as the candle shortens, substantially as and for the purpose specified.
3. A candle lamp including a cupped base having an outwardly extending annular flange formed with a corrugated upper face, and an upwardly tapering conical face above said corrugated face, a candle mounted in the base and a cap on the candle having the inner face of its lower end portion arranged to engage the conical face and its lower edge

face engage said corrugated face, substantially as and for the purpose set forth.

4. A candle lamp including a cupped base 35 having an outwardly extending annular flange formed with a corrugated upper face and also having a conical face above the flange, a receptacle in which the base is mounted having means for supporting the 40 base above and spaced apart from the bottom of the receptacle to form a receiving space below the base and passages from the upper part of the receptacle to the receiving space, a candle supported in the base and a 45 cap for the candle having its lower end movable into engagement with the corrugated face as the candle shortens, substantially as and for the purpose set forth.

5. A candle lamp including a cupped base 50 a receptacle below the base, the receptacle including an annular wall and inwardly and downwardly contracting portions, the base being supported on the portion of the bottom adjoining the annular wall and having 55 passages between its bottom and said portion of the bottom of the receptacle and a candle supported in the base, substantially as and for the purpose described.

In testimony whereof, I have hereunto 60 signed my name, at Syracuse, in the county of Onondaga, and State of New York, this 21st day of April, 1919.

EDWARD J. KNAPP.
